UNITED STATES PATENT OFFICE.

THOMAS O'BRIEN, OF NEW YORK, N. Y.

VELOCIPED.

SPECIFICATION forming part of Letters Patent No. 372,428, dated November 1, 1887.

Application filed February 18, 1887. Serial No. 228,016. (No model.)

To all whom it may concern:

Be it known that I, THOMAS O'BRIEN, of the city and State of New York, have invented an Improvement in Bicycles, of which the following is a specification.

In my present invention I make use of two wheels and a yoke-shaped frame passing at the sides of the main wheel and extending along to the socket for the fork of the steering-wheel, and I place the seat for one rider upon a standard rising from the main frame in front of the driving-wheel, and for the other rider upon standards at the rear of the machine; and the driving mechanism consists of pendent treadles and links connecting to cranks upon chain-wheels, having chains that pass to wheels upon the shaft of the main driving-wheel. The frame is braced to a yoke that passes over the driving-wheel, and to which the mud-guards are connected.

In some features my present invention is similar to that shown in my Patent No. 347,503, the present device, however, being a bicycle, and not a tricycle.

25 In my application No. 228,326, filed February 21, 1887, the frame receives the two driving-wheels of a tricycle, and there are two seats upon the frame. I do not, therefore, herein claim the two seats, one before the other, where the seats are between the two wheels.

30 In the drawings, Figure 1 is an elevation of the bicycle. Fig. 2 is a plan of the same. Fig. 3 is a separate plan view of the basket for holding luggage. Fig. 4 is a front view thereof.

The main wheel A and the front or steering-wheel, B, are of any ordinary construction.

40 C represents the fork of the steering-wheel, and 2 the mud-guard for the same.

3 are the side braces for holding the mud-guard, and 4 is the shaft or pivot for the forks and steering-wheel.

45 The main frame of the machine is preferably tubular; the side pieces, 5, of the said frame converge toward the front and back, and 6 is a half-circle connection at the back end, and 7 is the tubular socket, to which the side pieces, 5, converge, and to which they are connected, 50 and through this socket the pivot-shaft 4 passes.

This frame may be made of one pipe bent up

to shape, or it may be made of separate pieces of pipe coupled or brazed together.

The yoke 8 is attached at its lower ends to the side pieces, 5, of the frame, and it passes up over the main wheel A, and a pin, 70, projecting from this yoke, receives a socket, 9, into which a staff, 10, may be inserted carrying an umbrella or a flag, and there are braces 11 extending diagonally between the yoke 8 and the side pieces, 5, of the frame, to stiffen and strengthen said frame, and the mud-guards 12 are attached at their upper ends to the socket 9 and at the lower ends to the frame at the half-circle 6 and a cross-piece, 13, respectively.

55 The axle 14 of the wheel A is in bearings upon the under sides of the frame 5, and there are chain-wheels D upon the outer end of said axle, and endless chains 15 to the chain-wheels E, that are upon separate gudgeons or 60 shafts projecting from brackets 16, that extend down below the side pieces, 5, of the frame, and to these chain-wheels E the cranks 17 are attached, and from the crank-pin of each crank 17 there is a second crank, 18, extending so as to form compound cranks for the respective connecting-rods 20 and 21.

70 Upon the cross-piece 13 is a vertical standard, F, carrying the seat G, and said standard is preferably made as a column containing a rod, 22, at the upper end of which the seat is fastened, so that the seat can be raised or lowered and clamped by the screw 23. In Fig. 2 the metal frame of the seat G only is shown. The same, however, is to be 75 covered with leather or any othersuitable material.

80 The pendent links 25 26 hang from the front edge of the seat-frame G, and they are each preferably made of a tube with a rod inside 85 it, so as to vary the length to suit the rider, and the parts are clamped, when adjusted, by the screws 27. The foot-pieces or treadles H are applied at the pivots 29, that unite the lower ends of the respective links 25 26 and 90 connecting-rods 20.

95 It will now be understood that the rider, seated upon the seat G, propels the vehicle by the action of the feet upon the treadles H, the lower limbs of the leg swinging forward and 100 backward at the knee.

There is a second seat, K, upon standards

L, that are tubular, and the seat can be raised or lowered and clamped similar to the seat G, and there are pendent links 30 and treadles N upon the pivots 31, that unite the links 30 to the connecting-rods 21, and the rider upon the seat K aids in propelling the bicycle by moving the legs in a similar manner to the rider on the seat G; and it will be observed, upon reference to Figs. 1 and 2, that the compound cranks will not have any dead-center, because the crank-pins for the connecting-rods 20 pass the horizontal center plane after the crank to which the connecting-rods 21 are attached, thus equalizing the action 15 of the treadles.

Upon the upper end of the pivot-shaft 4 is a fork with lateral projecting tubes 35, through which passes a rod, 36, with handles 37 at the ends. By these the rider upon the seat G can 20 turn the pivot-shaft 4 and steer the bicycle, and the rod 36 can be partially revolved in the tubes 35, and in so doing the brake is applied, as next described.

The brake Q is upon the end of a lever, 38, 25 pivoted at 39, and to the upper end of the lever 38 a bent lever, O, is connected. The pivot 40 of this bent lever O is supported by a fork, 41, that extends out from the standard F, and the parts are strengthened by the braces 42, 30 that pass forward to the tubular socket 7. The arm 43 is fastened firmly to the rod 36, between the inner ends of the tubes 35, and there is a link, 44, extending from the arm 43 to the bent lever O, and the joints at the ends of this 35 link are preferably ball-joints to allow the pivot-shaft 4 to be turned in steering the bicycle without interfering with the brake, as the said brake is applied by swinging the handles 37 upwardly, turning the rod 36, and 40 moving the links and lever-connections to the brake. The weight of the handles 37 causes them to drop, when not in operation, and release the brake.

A step, 47, is applied at the back end to aid 45 in mounting to the seat K, and it is convenient to have a second step, 75, at the front part of the machine.

The steadyng-wheels 49 are at the lower ends 50 of the swinging bars 50, and these are pivoted at their upper ends to the side pieces, 5, of the frame, and there are slides 51 around the bars 50, and links 52 to short shafts 53 in bearings upon the under sides of the frame 5, and crank-arms 54 and links 55 to the arm 56 upon 55 a shaft, 57, that is provided with handles 58 at its ends, and said shaft is in bearings 59 upon the frame or arm 60, that extends out from the seat-frame K. By turning the handles 58 and shaft 57 the slides 51 will be raised 60 or lowered upon the swinging bars 50, and the links 52 will swing the bars 50 and steadyng-wheels 49 forward until the wheels rest upon the ground and hold the bicycle up vertically while the rider or riders mount into 65 the seats, or when moved in the opposite direction the steadyng-wheels are raised, as shown in Fig. 1.

In order to hold the parts in position, it is preferable to extend the arm 56 behind the shaft 57, and provide a swinging link, 62, with 70 a clamp-screw, 63, so that the link may be brought into action to clamp the arm 56 and hold the same when the wheels 49 are in contact with the ground, or when they are raised up from the same. 75

I provide a basket, P, preferably of wire-work, with a central opening in the bottom, so that the basket may be set over the socket 9, and the sides of this basket should extend downwardly and rest upon the pins 65, that 80 project from the braces 11; and it is preferable to arch the bottom of the basket, as seen in Fig. 5, so that it passes over or rests upon the mud-guards 12. This basket is adapted to carry bundles or baggage, and when not required it is easily lifted off. 85

It is preferable to make the mud-guards 12 of sheet metal, and trough-shaped sectionally, and to attach them by screw-bolts at their lower ends to the frame and at their upper ends to the 90 sides of the tubular socket 9, and this tubular socket 9 sets over a pin, 70, that projects at the upper end of the yoke 8, so that by removing the bolts at the lower ends of the mud-guards the socket 9 and the mud-guards can be lifted off 95 to give easy access for cleaning out the under sides of the mud-guards.

I claim as my invention—

1. The combination, in a bicycle, with the main driving-wheel and front steering-wheel 100 and its fork and pivotal shaft, of a tubular supporting-frame extending horizontally at the sides and passing around the back of the main wheel and connected at the front thereof, the converging side pieces, 5, and socket 7, 105 forming the forward part of said frame, bearings for the axle of the main wheel, connected to the tubular supporting-frame, the vertical yoke passing from the sides of the frame up over the main wheel, and the diagonal side 110 braces acting with the yoke to stiffen the horizontal frame, substantially as specified.

2. The combination, in a bicycle, with the main driving-wheel and front steering-wheel 115 and its fork and pivotal shaft, of a tubular supporting-frame extending horizontally at the sides and passing around the back of the main wheel and connected at the front thereof, the converging side pieces, 5, and socket 7, 120 forming the forward part of said frame, bearings for the axle of the main wheel, connected to the tubular supporting-frame, the vertical yoke passing from the sides of the frame up over the main wheel, and the diagonal side 125 braces acting with the yoke to stiffen the horizontal frame, and vertical tubular columns upon said frame at the front and rear of the main wheel, and the seat-rods and seats supported by said columns, substantially as set forth. 130

3. The combination, in a bicycle, with the main driving-wheel and front steering-wheel and its fork and pivotal shaft, of a tubular supporting-frame extending horizontally at

the sides and passing around the back of the main wheel and connected at the front thereof, the converging side pieces, 5, and socket 7, forming the forward part of said frame, bearings for the axle of the main wheel, connected to the tubular supporting frame, the vertical yoke passing from the sides of the frame up over the main wheel, and the diagonal side braces acting with the yoke to stiffen the horizontal frame, and vertical tubular columns upon said frame at the front and rear of the main wheel, and the seat-rods and seats supported by said columns, and pendent links from the seat-frames, treadles, and cranks, and connecting-rods for driving the main wheel, substantially as set forth.

4. The combination, in a bicycle, of main and steering wheels, a frame passing around the main wheel and connecting the two wheels, 20 a vertical column and seat in front of the main wheel, two vertical columns upon the rear part of the frame at each side of the main wheel, and a seat-frame upon said columns, pendent links from the respective seat-frames, treadles, 25 connecting-rods, cranks, chain-wheels, and

chains, by which the main axle and wheel are driven, substantially as set forth.

5. The combination, in a bicycle, with the side frames and steadyng-wheels 49, of the swinging bars 50, links 52, and crank-arms 54, 30 pivoted to the side frames, the slides 51, connecting the bars 50 and links 52, the shaft 57, and handles 58, and the links 55 and arms 56, connecting the crank-arms and handle-bar or shaft 57, respectively, whereby the swinging 35 movement of the handles operates the steadyng-wheels, substantially as specified.

6. The main wheel A, brake Q, steering-wheel B, and its fork and pivot-shaft, in combination with the lever 38, bent lever o, the 40 link 44, arm 43, and the handle-bar, tube, and handles, whereby the movements of the handles actuate the brake, substantially as specified.

Signed by me this 15th day of February, 45 1887.

THOMAS O'BRIEN.
